ATTORNEY

UNITED STATES PATENT OFFICE.

ENOS H. KREIDER, OF LANCASTER, PENNSYLVANIA.

SHOCK-ABSORBER.

1,155,738.

Specification of Letters Patent.

Patented Oct. 5, 1915.

Application filed October 22, 1913. Serial No. 796,693.

To all whom it may concern:

Be it known that I, ENOS H. KREIDER, a citizen of the United States, residing at Lancaster, in the county of Lancaster and

5 State of Pennsylvania, have invented certain new and useful Improvements in Shock-Ab-sorbers, of which the following is a specifica-tion, reference being had therein to the accom-panying drawing.

10 This invention relates to shock absorbers of that class employed on automobiles by which a gradually increasing resistance is interposed between the body of the car and the running gear to compensate for the 15 movement of the springs in either direction beyond a predetermined limit.

The object of the invention is to provide a device of this class which shall be simple, durable and efficient, and easily attached to 20 automobiles of the usual type.

Another object of the invention is to pro-vide a shock-absorber that will allow the 25 springs of the vehicle to have a perfectly free movement both up and down within certain limits before the device starts to act.

Still another object is to provide a device that will be equally effective for a downward movement of either the body or the running gear or an upward rebound; and further, 30 that when such movement approaches the extremes the efficiency of the device will be greatly increased, and in an automatic manner.

A further object of the invention is to 35 produce a friction shock-absorber that does not interfere with the free action of the spring at the time the road obstruction is encountered, but instantly retards the ex-cessive upward tendency of the body of the 40 vehicle which is caused by the recoil of the springs. The same device prevents the sud-den drop of the body when the wheels en-counter a depression in the road.

45 A further object is to produce a shock-absorber that automatically prevents the shock to the body of the vehicle by vary-ing resistance and in proportion to the vary-ing recoil pressure to which the body of the ve-hicle is subjected.

50 A further object is to produce a shock-absorber that prevents the sudden drop of the body of the vehicle when the wheels en-counter a depression in the road by auto-matically imparting an upward yielding 55 pressure to the body. Force of upward

pressure is in proportion to the violence of the dropping tendency of the body of the vehicle.

With these and other objects in view, my invention consists in certain construction 60 and combination of parts as will hereinafter be fully described and claimed in the an-nexed specification and illustrated in the accom-panying drawings, in which like figures of reference refer to corresponding parts in 65 all of the views; but it is fully understood that while I have here described my inven-tion as shown that I do not confine myself to the exact design, as slight changes may be made in the construction and arrange-70 ment of the several parts without depart-ing from the spirit of the invention.

In the drawings:—Figure 1, is a side ele-vation of the device as applied to an auto-mobile. Fig. 2, is an end view of the same. 75 Fig. 3, is an enlarged detail side view with one-half of the case removed. Fig. 4, is a longitudinal sectional view on the center line.

Referring to the drawings:—The device 80 comprises a case divided longitudinally into two halves 10, and 11, and having arms 12, and 13, integral therewith. Within said case are mounted two friction disks 14, and 15, which are formed with flanges 16, and 17, and hubs 18, which are mounted in cen-tral orifices formed in said case halves 10, and 11. Exten&ng through said disks 14, and 15, in axial relation thereto is a shaft 90 formed with an enlarged central portion or bearing 19, having on each side thereof the squared portions 20, which are engaged by squared orifices in the disks 14, and 15, in such a manner that said disks are rigidly se-cured from turning on said shaft, while the 95 disk 14, is secured by the pin 21, to the bracket 22, by which the device is mounted to the frame 23, of the vehicle, and in this manner both disks 14, and 15, and the shaft remain stationary while the case members 100 can freely rotate upon the hubs 17, and 18.

Rotatably mounted upon the bearing 19, are a pair of circular friction plates 24, which are retained within the flanges 16, of the disks; while between said plates 24, is placed a plate 25, formed with ratchet teeth 26. Said disks, plates and ratchet plate are all held in frictional engagement by a spring washer 52, and a nut 27, threaded upon the outer end of the shaft; while the inner end 110

of said shaft is held on the bracket 22, by a nut 28, threaded thereon. Said shaft is supplied with an oil hole and cup 29.

Between the arms 12, and 13, at a point adjacent to the ratchet disk is a transverse pin 30, upon which is mounted a pawl 31, formed with two arms 32; while between said arms 32, is placed another pin 33, formed with a V-shaped notch 34, in the side thereof, into which snaps a ball 35, which is held in contact with said pin 33, by a spring 36, contained within said pawl 31. The outer ends of said arms 12, and 13, are held together by a screw 37, and are also provided with a bolt 38, upon the outer ends of which are pivoted the upper ends of the links 39, which have their lower ends pivoted to a stud bracket 40, secured to the axle 41, of the vehicle.

20 The pawl 31, is provided with two rearwardly extending flat springs 42, secured thereto by the screws 43. The rear ends of said springs 42, are formed with an S-curve 44, adapted to engage the sides of a cam pin 45, secured in the bolt 38, in such a manner that as the arms 12, and 13, are moved either upward or downward by the action of the vehicle spring 46, the cam 45, will act upon one of the springs 42, to swing the pawl 31, on the pin 30, and bring one of its arms 32, into engagement with the ratchet teeth 26, on the plate 25, and lock the same so that it moves with the arms 12, and 13, and rotates between the friction disks 24, when 35 the frictional engagement will retard the free movement of the arms 12, and 13.

By referring to the Fig. 3, it will be seen that the arms have sufficient movement before the pawl is actuated, and the friction device employed, to give the vehicle springs free action for small bumps, etc. It will also be noted that the ball lock 35, which rides easily over the sides of the V-notch 34, tends to instantly bring the pawl 31, back to its normal position.

For controlling the point where the pawl shall start to engage the ratchet, one end of the bolt 38, is squared as at 47, and has secured thereon by the nut 48, a lever 49, formed with a seat 50, for engagement with one of a series of notches 51, formed in the link 39, so that the bolt may be moved to adjacent the position of the cam.

The frictionally held ratchet wheel within 55 the casing, with the pawl ends engaging the same, when the arm of the casing is moved causing the ratchet wheel to rotate in either

direction imparts, during this time, a retarding effect to the body of the vehicle.

This constitutes a device operating on the 60 springs of the vehicle which automatically causes the pawl points to engage the ratchet wheel at such times only when a retarding effect is desired. The same device operating 65 the two springs, automatically causes the 65 pawl points to disengage during a desired period of time, thus giving free action of the springs while the wheel of the vehicle is adjusting itself to an obstruction or a depression on the road, and instantly causes the 70 pawl points to engage the ratchet at the moment the return movement begins.

Having thus described my invention what I claim as new, and desire to secure by Letters Patent is:—

75

1. In a shock absorber of the class described, the combination with a vehicle running gear having a body secured thereon by springs, of a bracket secured to said body, a shaft secured to said bracket, a casing 80 formed with an arm and mounted on said shaft, a ratchet wheel rotatably mounted on said shaft within said case, a pair of friction plates rotatably mounted on said shaft on each side of said ratchet wheel, a second 85 pair of friction plates embracing the first pair and rigidly secured upon said shaft and to said bracket, a spring tension on the end of said shaft for varying the frictional contact of said plates, a pawl mounted in 90 the arm of the casing and adapted to engage said ratchet when the arm is moved in either direction, a link pivoted to the end of said arm and connected to the running gear of the vehicle, and means carried by the pivot 95 of said arm and link to operate said pawl to engage the ratchet wheel either above or below the center line thereof.

2. In a shock absorber of the class described, the combination with a combined 100 casing and arm, having a pair of friction disks mounted within the casing, of a ratchet wheel mounted within said casing in coaction with said disks, spring actuated pawl points mounted within the arm, said pawl 105 points adapted to engage the ratchet wheel when the arm is moved upward or downward for a predetermined distance.

In testimony whereof I affix my signature in presence of two witnesses.

ENOS H. KREIDER.
